UNITED STATES PATENT OFFICE.

OSCAR V. PAYNE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

MULTIPLE-NEEDLE WEFT DETECTOR.

Application filed June 4, 1926. Serial No. 113,794.

This invention relates to improvements in multiple needle weft detectors for looms of the type shown in patent to Ryon No. 1,221,768 and it is the principal object of the invention to simplify the construction of a detector of this type to the end that close fitting and excessive machining operations may be avoided.

The yarn engaging elements of detectors of this type usually have two parallel arms which pass through either milled slots or drilled holes but it has been found that considerable fitting is required to have both arms move freely. The upper portion of the 10 yarn engaging element has usually been the controller for the loom actuator and it is a further object of my invention to provide a yarn engaging element the bearing portions of which are in alignment to the end 15 that a single machining operation will provide the requisite bearings for the elements.

It is a further object of my invention to provide each detector element with an 20 upstanding controller to cooperate with supporting guides formed on each side of the complement of detecting elements, the guides 25 serving to hold the elements and the controller portions thereof in proper position.

It is a still further object of my invention to provide a support for the detecting elements having a boss under the controllers on which the detecting elements rest to take 30 the downward pressure of the actuator lever and thus relieve the detecting elements of 35 strain.

With these and other objects in view which will appear as the description proceeds, my invention resides in the combination and arrangement of parts hereinafter 40 described and set forth in the claims.

In the accompanying drawings wherein I have shown a convenient embodiment of my invention,

Fig. 1 is a vertical section through the detector and lay parts, showing the detector in the position it assumes when first cooperating with the surface to be detected,

Fig. 2 is a top plan view of the detector looking in the direction of arrow 2, Fig. 1,

Fig. 3 is a vertical section on line 3-3 of Fig. 2, and

Figs. 4, 5, and 6 are enlarged detail vertical sections on lines 4-4, 5-5, and 6-6, respectively, of Fig. 1.

Referring particularly to Figs. 1 and 2 it will be seen that I have provided a stand 10 to which is bolted a support 11 having a rib 12 formed on the upstanding portion thereof. A bed 13 has a depending foot 14 with a notch to receive the rib 12, said foot and support having aligning openings through which extends a spring 15 the forward end of which is secured to a finger 16 depending from the bed 13 and the rear end of which extends through the openings and is held in position by a pin 17 having contact with the rear face of the support 11. Said spring provides for yielding forward movement of the bed such as might result should a bobbin be caught between the same and the advancing lay. The forward end of the bed is thickened as at 18 and has cut therethrough a series of parallel vertical slots 19 which are in alignment with another set of parallel vertical slots 20 cut in a thickened portion 21 located at the rear of the bed 13.

Slidably mounted on the bed is a plurality of needle detectors 22 which project rearwardly to enter a slot 23 formed in the shuttle S to cooperate with the bobbin B. The latter is provided with a plurality of holes 24 which may be arranged as shown either in Patent No. 1,220,685 or No. 1,337,706, the holes being arranged in parallel planes and staggered angularly so that when the yarn has been woven off the bobbin a portion of at least one of the holes will lie opposite one or another of the needle detectors 22.

The forward end of each detector is upturned as at 25 to cooperate with a stud 26 formed in the transferring member T. At the time of transfer the stud 26 will move to the left from the full to the dotted line position shown in Fig. 1 to withdraw the detectors from the path of the incoming bobbin. Each of the wires 22 has soldered, brazed, welded or otherwise secured thereto a controller member 27 having a lower horizontal arm 28 formed with a concave longitudinal groove which receives a portion of the upper surface of the corresponding wire 22 as shown in Fig. 6. Each of said controllers has a forwardly extending guard 29 and an upstanding trip 30 to cooperate with the actuator lever 31 of the usual construction.

Said detecting wires 22 or elements are held in proper position by a cap 32 held to

the bed by means of screws 33 and have a forwardly extending horizontal portion to extend over a portion of the slots 19 to restrict upward movement of the forward 5 part of the needle detectors 22. The rear portion of the cap extends over the slots 20 and cooperates therewith to hold the yarn engaging portions of the detector wires in proper position as set forth in Fig. 5.

10 The cap is provided with a pair of separated walls 34 which stand up from the central side portions of the cap and are so located as to position the guards 29. The latter substantially fill the space between 15 the walls and thus insure proper positioning of the detector wires 22. The central portion of the cap is cut away as at 35 to permit free movement of the lower horizontal arms 28 of the controller members 27. The 20 rear edge 36 of the opening 35 limits rearward movement of the detectors under action of coil springs 37, one of which surrounds each detector and lies between the thickened portion 18 and the controller member 27.

Under normal conditions when sufficient yarn for continued weaving is present the bobbin B will move forward with the lay and all of the detector wires 22 will slide 30 forwardly in bed 13 against the action of the springs 37 to move the controllers 27 from under the actuator lever 31. When the lay is on front center the actuator is given a downward movement and when it 35 is uninterrupted in this movement no change takes place in the loom. When the weft has been depleted, however, one or another of the detector needles 22 will enter a hole 24, being held in this position by its spring, 40 and although the remaining detectors will be moved forwardly by the bobbin yet the one entering the hole in the bobbin will remain under the actuator lever 31 and downward movement of the latter will therefore 45 be prevented, a condition which as explained in Patent No. 1,030,748 is accompanied by an indication of weft exhaustion to the magazine. Downward pressure of the actuator lever is transferred to the boss 38 formed on 50 the bed 13 and lying immediately under the vertical portion of the controller member 27. In this way the detector needles are relieved of any strain to which they might otherwise be subjected by the actuator.

55 From the foregoing it will be seen that I have provided a simple form of detector for multiple needle weft detectors having the bearing portions thereof in alignment and requiring but one machining operation to 60 provide the guides for the needles. Proper positioning of the latter is insured by the guards 29 which substantially fill the space between the walls 34 and the detecting elements are relieved of any lateral strain by 65 the boss 38.

Having thus described my invention it will be apparent that changes and modifications may be made therein by those skilled in the art without departing from the spirit and scope of the invention, and I do not 70 wish to be limited to the details herein disclosed but what I claim is:

1. In a weft detector for looms to cooperate with a bobbin having a plurality of holes therein to be uncovered at substantial exhaustion of weft, a plurality of individually movable detectors to cooperate with the bobbin, a support for the detectors, an actuator, a pair of spaced walls on the support, and a controller for the actuator secured to each 75 detector, portions of said controllers supporting each other and located between the walls, the controller corresponding to the indicating detector cooperating with the actuator to effect a change in the operation 80 of the loom.

2. In a weft detector for looms to cooperate with a bobbin having a plurality of holes therein to be uncovered at substantial exhaustion of weft, a plurality of individually 85 movable detectors, a support therefor having aligning guideways, each detector having a substantially straight portion lying in the corresponding guideways, a controller secured to and upstanding from each detector, an actuator for the controllers, and relatively fixed spaced means to support the controllers against lateral movement, portions of the controllers substantially filling 90 the space between said means so that said controllers support each other.

3. In a weft detector for looms to cooperate with a bobbin having a plurality of holes therein to be uncovered at substantial exhaustion of weft, a plurality of individually 95 movable detectors, a support therefor having aligning guideways, each detector having a substantially straight portion lying in the corresponding guideways, a controller secured to and upstanding from each detector, an actuator for the controllers, and relatively fixed spaced means to support the controllers against lateral movement, portions of the controllers substantially filling 100 the space between said means so that said controllers support each other, said support having portions to engage the detectors at points substantially under the controllers to support said detectors when the controllers 105 are engaged by the actuator.

4. In a weft detector for looms to cooperate with a bobbin having a plurality of holes therein to be uncovered at substantial exhaustion of weft, a plurality of individually 110 movable detectors, a support therefor having aligning guideways, each detector having a substantially straight portion lying in the corresponding guideways, a controller secured to and upstanding from each detector, an actuator for the controllers, and relatively fixed spaced means to support the controllers against lateral movement, portions of the controllers substantially filling 115 the space between said means so that said controllers support each other, said support having portions to engage the detectors at points substantially under the controllers to support said detectors when the controllers 120 are engaged by the actuator.

- tively fixed spaced means to support the controllers against lateral movement, portions of the controllers substantially filling the space between said means, each controller 5 having a portion extending therefrom and in substantial engagement with corresponding portions of the adjacent controllers so that said controllers support each other, said portions preventing lateral displacement of 10 the controllers when one of the detectors is received by a hole in the bobbin and the other detectors are moved forwardly.
5. In a weft detector for looms to cooperate with a bobbin having a plurality of holes 15 therein to be uncovered at substantial exhaustion of weft, a plurality of individually movable detectors to cooperate with the bobbin, a support for the detectors, a pair of spaced walls extending from the support, a 20 controller secured to each detector, portions of said controllers extending between the walls and substantially filling the space between said walls so that the controllers are supported by each other, each detector hav- 25 ing an upstanding portion, said upstanding portions being independent of each other, and transfer mechanism to engage the up- standing portions, said portions being held in proper position for engagement by the transfer mechanism by reason of the fact 30 that the controllers and walls are in engagement with each other.
6. In a weft detector for looms to cooperate with a bobbin having a plurality of holes 35 therein to be uncovered at substantial exhaustion of weft, a plurality of individually movable detectors to cooperate with the bobbin, a support for the detectors, a pair of spaced walls extending from the support, a controller secured to each detector, portions 40 of said controllers extending between the walls and substantially filling the space between said walls so that the controllers are supported by each other, transfer mechanism, and vertically extending spaced portions 45 of the detectors lying in front of a portion of the transfer mechanism to be engaged by the latter on a transferring pick of the loom, said portions in front of the transfer mechanism being held in proper 50 vertical position by the mutual engagement of the walls and controllers.

In testimony whereof I have hereunto affixed my signature.

OSCAR V. PAYNE.
